WHOLE No. 1,460.

Carpet Pattern.

ELEMIR J. NEY, OF LOWELL, MASSACHUSETTS,

ASSIGNOR TO THE LOWELL MANUFACTURING COMPANY.

Letters Patent for a Design No. 95, dated August 13, 1861.

SPECIFICATION.

TO ALL WHOM IT MAY CONCERN:

Be it known, that I, ELEMIR J. NEY, of Lowell, in the county of Middlesex and State of Massachusetts, have originated and designed a new Pattern for Carpets, of which the following is a full, clear, and exact description, reference being had to the accompanying drawings making part of this specification.

Fig. A is a group, consisting of a large rose, three large leaves, and several smaller ones.

Fig. B is a group similar to fig. A.

Fig. C is a broad band, composed of small blocks and key-work, extending from corner 1 to corner 2. Bands 3 and 4 are similar to C, and run parallel with each other, the one running under and the other crossing the band C at right angles with it.

When matched, these bands enclose large diamonds, on which rest groups A and B. In the corners of the diamonds are small groups of leaves and flowers.

The colors employed for the different portions of the design may be varied to suit the taste and wish of the manufacturer.

Claim.

What I claim as my invention, and desire to secure by Letters Patent, is—
The design or pattern for carpets or other fabrics herein set forth.

E. J. NEY.
